(57) **CLAIM**

The ornamental design for a rack for surface mounting, as
shown and described.

DESCRIPTION

FIG. 1 is a perspective view of a rack showing our new
design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a perspective view of a plurality of racks of FIG.
1.

FIG. 9 is another perspective view of a plurality racks of
FIG. 1; and,

FIG. 10 is still another perspective view of a plurality racks
of FIG. 1.

The broken lines shown in the figures represent portions of
the rack for surface mounting that form no part of the
claimed design.
